UNITED STATES PATENT OFFICE

GOTTLOB BITZER, OF WYOMISSING, PENNSYLVANIA, ASSIGNOR TO TEXTILE MACHINE WORKS, OF WYOMISSING, PENNSYLVANIA, A CORPORATION OF PENNSYLVANIA

LOOP-REGULATING MECHANISM FOR FULL-FASHIONED KNITTING MACHINES

Application filed June 18, 1929. Serial No. 371,761.

My invention relates to straight or full fashioned knitting machines, and more particularly to improved automatic loop regulating mechanism therefore.

5 One object of my invention is to provide novel and simplified automatic loop regulating mechanism for straight knitting machines, adapted to cooperate with automatically adjustable yarn control mechanism, for 10 effecting the addition of plating or reenforcing threads at desirable parts of the knitted fabric.

Another object is to coactively combine such automatic loop regulating mechanism 15 and yarn control mechanism with adjustable pattern actuating means so that the possible production of ornamental plating or reenforcing effects is practically unlimited.

The invention comprises the new elements, 20 features of construction, and novel arrangement of parts in operative relationship as herein exemplified, while its essence and scope are indicated in the appended claims.

The above, and other features, will become 25 more readily apparent from the following detailed description of one embodiment of the invention, reference being had to the accompanying drawings in which:

Fig. 1 is a vertical cross-sectional view 30 taken near the left end of a full fashioned knitting machine, having my invention applied thereto, certain of the parts being omitted.

Fig. 2 is a fragmentary front elevational 35 view of certain parts of the machine shown in Fig. 1.

Fig. 3 is a sectional view taken as indicated by the arrows 3-3 in Fig. 2.

Fig. 4 is a section on line 4-4 of Fig. 3.

40 Fig. 5 is a section on line 5-5 of Fig. 4.

Fig. 6 is a section on line 6-6 of Fig. 3.

Fig. 7 is a section on line 7-7 of Fig. 4.

Fig. 8 is an enlarged end elevational view, partly broken away, of a certain part of the 45 machine shown in Fig. 1, taken as indicated by the arrows 8-8 in Fig. 2.

Fig. 9 is a rear elevational view of the mechanism shown in Fig. 8, and as seen by looking in the direction indicated by the ar- 50 row A in said figure.

Fig. 10 is a sectional view similar to Fig. 6 but of a modified form of construction.

Fig. 11 is a section taken substantially as indicated by the arrows 11-11 in Fig. 10 and includes parts not shown in Fig. 10.

The general construction and operation of the full fashioned knitting machine to which my invention relates, is well known, and therefore only such parts of the machine directly pertaining to, and involved in the operation of the invention have been illustrated.

The common needle bar presser mechanism, more fully disclosed in the Melchior Zwickly Patent #1,608,285, granted November 23, 1926, and thread control mechanism are cooperatively combined with adjustable pattern actuating means to effect determined additional lengthening of the loops during their formation, at the points in the fabric where it is desired to add plating or reenforcing threads; such action in no way interfering with the usual loop-forming movements ordinarily imparted by the cam shaft.

The loop-regulating shaft 15, receives well known cam determined turning movements from the cam shaft 16, which are transmitted to the pivotally carried needle-bar 17, through presser lever 18 and connection 19, to vary the position of the needle-bar 17 relative to the sinkers, for the purpose of lengthening the loops sufficiently to accommodate the yarn ordinarily laid by the yarn guide carrier bars 20. This action is more fully described in Gottlob Bitzer Patent No. 1,694,888 granted December 11, 1928.

The mechanism comprising my invention imparts additional or supplemental loop-lengthening movements to the needle-bar 17 so as to increase the ordinary loop a sufficient amount to accommodate a second thread, such movements being imparted to the loop-regulating shaft 15 by the mechanism about to be described.

Fixed to the shaft 15 is an arm 21, provided at its upper end with a laterally shiftable, and freely rotatable roller 22, adapted to be engaged and determinedly moved by a specially constructed and controlled radially expandible cam device comprising impelling

segments 23 and 24 radially shiftable on a mounting plate or disk 25 secured to cam shaft 16 by set screws 26.

A roller shift lever 27 for throwing the 5 roller 22 into or out of action, is pivoted on the arm 21 at 28 and is provided with a yoke 29 in engagement with the grooved flange 31 on roller 22. The lower end of lever 27 abuts against a stop 32 to limit its movement 10 when roller 22 is shifted to its active position.

By referring more particularly to Figs. 6 and 7, it will be noted that the segments 23 and 24 are radially shiftable or swingable between mounting plate 25 and a semi-circular plate 34 separated therefrom by a spacing element 35. The outer ends of segments 23 and 24 are slotted centrally to accommodate links 36 and 37 which are retained therein by pins 20 38 and 39 as shown. Links 36 are held in the cut-out part of spacing element 35 by pins 40, which extend through the walls of the plate and through plates 34 and 25 while links 37 are similarly fastened by pins 41 25 extending through mounting plate 25 and plate 34. Pins 40 and 41 extend beyond the outside of plate 25, and are in slotted engagement with, and held against axial movement, by locking plates 45 secured to plate 25 by 30 screws as indicated in Fig. 1.

Pins 46 are fixed in the segments 23 and 24 and extend through openings in spacing element 35, a tension spring 35a being connected to their free ends to hold the segments 35 in their normal or inactive position.

Each of the segments 23 and 24 is provided with an anti-friction engaging roller 47 adapted to coact with one or two similarly adjustably held cams 48 and 49 loosely carried by the cam shaft 16 and adapted to shift the segments radially.

The various regulated positions of cams 48 and 49 determines the time and extent of the supplemental loop-lengthening movements 45 imparted to the loop regulating shaft 15 by the segments 23 and 24.

Cams 48 and 49 are adjacent each other, slightly separated, and loosely mounted concentrically on the cam shaft 16 between the 50 mounting plate 25 and a retaining collar 51 fixed to the cam shaft, as shown in Figs. 4 and 7.

Secured to the cams 48 and 49 are screw studs 50 and 52 having a ball formed at their 55 outer ends adapted to engage in adjustable sockets and forming universal joints 53 and 54 therewith. The cams 48 and 49 are held in adjusted non-rotating positions by rods 55 and 56, adjustably secured to the joints 53 and 54 and connected with the double-ended arm of a bell crank lever 56a, which in turn is connected to the bottom end of a vertical lever 57 through the link 58. The connections 60 just described are adjustable and provided with universal joints, as shown. Lever 57 is

fulcrumed at 59 on a bearing 61 secured to a frame connecting channel 62.

The supplemental loop-lengthening movements are synchronized with the laying of reinforcing or plating threads commonly supplied to determined needles only, and to attain such synchronization, I preferably control the movements of the cams 48 and 49 by the regulating screw mechanism limiting the varied feeding traverse of the carrier 75 rods 20.

It will be apparent that by moving the lever 57 to and fro, the cams 48 and 49 will be moved toward and from each other around cam shaft 16 by the mechanism already described. To thus move the lever 57, a block 63 is pivotally mounted in the upper bifurcated end of the same, which slidably engages with extension on collars 65 and 66 adjustably secured to reciprocable rod 67 slideable in suitable bearings (not shown) and connected with a rod 68 through a link 69. Rod 68 is fixed to one of the yarn carrier stop nuts 71, at 72. These nuts control the special plating or reenforcing yarn carriers 80 20, and are mounted on a common reversely threaded spindle 73 which is automatically rotatable in either direction. Movement of the spindle causes stop nuts 71 to move toward or from each other and such action is 85 95 simultaneously transmitted to cams 48 and 49 through the connections described, so that they will likewise move toward or from each other in synchronism with the nuts 71.

Two ratchet wheels 74 and 75 are fixed to 100 the end of the spindle 73 which coact with pawls 76 and 77 to rotate the spindle step by step, alternately, in either direction. The pawls 76 and 77 are similar and each is provided with a flange as indicated at 78 and 80 engageable by the fingers 79 and 81 secured to the upper end of a lever 82 which is moved to alternately bring one or the other of said fingers into engagement with the flange of its cooperating pawl to prevent it 105 from coacting with its respective ratchet wheel at a time when both pawls are simultaneously shifted.

Pawl 76 is mounted on a lever 83 fulcrumed on spindle 73, said lever being adjustably connected by a link-and-lever connection 84, 85 and 86 with a similar lever 90 which carries the pawl 77 and is likewise pivoted on the spindle 73. Thus the pawls are connected to move in unison, however only one being active at one time, and are actuated by a rod 87 connected with a lever 88 fulcrumed on a bearing 89 and carrying a roller 91 engageable with a cam 92 on cam shaft 16. One end of lever 88 rests on the shouldered end 110 of a lever 93 which is operated by a well-known pattern chain 94 provided with actuating buttons or studs 95 and 96.

Low buttons 95 are provided on the chain 115 for moving lever 93 sufficiently to disengage 130

its upper end from the lever 88 thereby allowing roller 91 to rest on cam 92 and coact therewith to cause the active pawl 77 to move its respective ratchet wheel 75 and consequently turn the spindle a step in one direction. When the button has passed, a tension spring 97 acts to return the lever 93 into engagement with lever 88 and retains it in inactive position after one revolution of cam 92.

High buttons 96 are provided on the chain which move the lever 93 an increased amount thereby again allowing cam 92 to act as before, however this time the increased movement of lever 93 will also bring its upper end into engagement with, and shift a lever 98 held in the position shown by a spring 99, and fulcrumed at 100 and connected with the lower end of lever 82 by a rod 101, moving the same to disengage finger 79 from the flange 78 on pawl 76 and bringing finger 81 into active engagement with flange 80 on pawl 77. This action will allow pawl 76 to act on ratchet wheel 74 while pawl 77 will be held inactive during the pawl shift motion derived from cam 92, causing the spindle to be moved a step in the opposite direction.

After a high button 96 has passed, the tension spring 99 will again return the lever 98 to its normal position, thereby reversing the connection of fingers 79 and 81, while the levers 88 and 93 are reset for cooperation with the next button.

Figs. 10 and 11 illustrate a modified form of segment construction and mounting therefore. In this instance, the mounting plate 25a is provided with two radial grooves or recesses 30 and 50 in which impelling segments 23a and 24a are slidably mounted and confined by a retaining plate 34a as shown. A tension spring is mounted in a central groove of each segment and connected with the same and the mounting plate to hold the segments in inactive position as clearly illustrated. Rollers 47a are secured to the segments as before, which are acted on by the cams 48 and 49.

It is to be understood that two or more of the loop-regulating units may be mounted in the machine at various points and operatively connected with the slide rod 67, so as to reduce the torsional strain on the cam and regulating shafts.

It is also to be understood, that the slide rod 67 may be connected with other actuating means for certain purposes, for example with one of the narrowing nuts commonly employed.

Operation

When the machine is in operation, and the loop-regulating mechanism "thrown in" by properly shifting roller 22, the stop nuts 71 are moved in accordance with the arrange-

ment of the low and high buttons on the pattern chain 94, and the cams 48 and 49 are simultaneously moved toward or from each other. As the cam shaft 16, and consequently mounting plate 25 is rotated, the rollers 47 will engage with, and be moved radially by the cams 48 and 49, thereby causing impelling segments 23 and 24 to partially turn the loop-regulating shaft 15 and actuate the presser mechanism. During each revolution of the cam shaft 16 the regulating shaft 15 will be moved twice, and held in active position during the time the lengthened loops of the fabric are supplied with an extra thread. The timing of this action is varied by the relative position of the cams 48 and 49 and their engagement with rollers 47, which corresponds with the varied time required for laying the extra thread by the yarn carriers.

Referring more particularly to Fig. 4 and considering that segment 23 cooperates with cam 48, while segment 24 cooperates with cam 49, it will be apparent that by moving these cams toward and from each other the time at which segments 23 and 24 are shifted radially will be varied and consequently that the total length of time during which the cam 21 is held in shifted position depends on the relative position of these segments. If segment 23 and cam 48 coact, shifting of the roller 22 takes place after roller 47 of segment 23 engages and is shifted by the forward edge of cam 48, and when the forward edge of the shifted segment engages roller 22. The arm 21 then remains in the shifted position until roller 47 drops off the rear edge of cam 48.

If the cam 49 and segment 24 cooperate, the latter is shifted when the roller 22 is at a particular determined point of its coacting arcuate edge, so that the time of such shifting action is the time when roller 47 of segment 24 first engages the forward edge of cam 49 and is shifted radially (simultaneously shifting roller 22) until the roller 22 drops off the rear edge of segment 24.

In either case, the total time of shifting is the same for any particular adjustment of the expansible cam, that is, the loop regulating mechanism is operated for the same length of time when cam 48 and segment 23 cooperate and when cam 49 and segment 24 cooperate.

In this manner the control of cams 48 and 49 toward and from each other makes it possible to control the time of action, as well as to vary the total length of time that the segments 23 and 24 hold the arm 21 in shifted position.

Of course, the automatic loop-regulating mechanism shown and described, may be changed in various ways, and variations may be required under certain conditions, therefore, while some of the constructional details are deemed preferable and I have shown and

described these specifically, I do not wish to be understood as being limited to such construction, but consider that I am at liberty to make such changes and alterations as fairly come within the scope of the appended claims.

I claim:

1. In a straight knitting machine the combination with a cam shaft and needle-bar presser mechanism operated thereby; of supplemental actuating means for the presser mechanism comprising a radially expansible cam device carried by said cam shaft.
2. In a straight knitting machine the combination with a cam shaft, and needle-bar presser mechanism including a regulating shaft, operated thereby; of a radially expansible cam carried by said cam shaft operative to actuate said regulating shaft.
3. In a straight knitting machine the combination with a cam shaft and needle-bar presser mechanism operated thereby; of a radially expansible cam carried by said cam shaft operative to actuate said mechanism during a partial rotation of the cam shaft.
4. In a straight knitting machine the combination with a cam shaft and needle-bar presser mechanism operated thereby; of a radially expansible cam device carried by said cam shaft operative to actuate said mechanism, and stationary adjustably positioned means for expanding said cam.
5. In a straight knitting machine the combination with a cam shaft and needle-bar presser mechanism operated thereby; of a radially expansible cam device carried by said cam shaft operative to actuate said mechanism, stationary adjustable means for expanding said cam, and mechanism for adjusting said means.
6. In a straight knitting machine the combination with a cam shaft and needle-bar presser mechanism operated thereby; of a radially expansible cam device carried by said cam shaft operative to actuate said mechanism, stationary adjustable means for expanding said cam comprising a non-rotatable adjustable cam.
7. In a straight knitting machine the combination with a cam shaft and needle-bar presser mechanism operated thereby; of a radially expansible cam device carried by said cam shaft operative to actuate said mechanism, a non-rotatable adjustable segmental cam for expanding said device, and means for moving the segments of the segmental cam towards and from each other.
8. In a straight knitting machine the combination with adjustable yarn control mechanism, needle-bar presser mechanism, and a cam shaft operative upon the latter; of supplemental actuating means for the presser mechanism comprising a radially expansible cam carried by the cam shaft, adjustable

mechanism for expanding said cam, and means for adjusting the yarn control mechanism and cam expanding mechanism in synchronism.

9. In a straight knitting machine the combination with cooperating yarn guide carrier bars, a reversely threaded spindle for controlling the traverse of said bars, needle-bar presser mechanism, and a cam shaft operative upon the latter; of supplemental actuating means for the presser mechanism comprising a radially expansible cam, and means controlled by said reversely threaded spindle for expanding said cam.

10. In a straight knitting machine the combination with cooperating yarn guide carrier bars, a reversely threaded spindle for controlling the traverse of said bars, needle-bar presser mechanism, and a cam shaft operative upon the latter; of supplemental actuating means for the presser mechanism comprising a radially expansible cam carried by said cam shaft; and non-rotatable means carried by said cam shaft for expanding said cam cooperatively connected with said spindle.

11. In a straight knitting machine yarn control mechanism comprising a reversely threaded spindle, thread carrier stop nuts on the spindle, and pattern controlled means for turning the spindle in either direction; a cam shaft; needle-bar presser mechanism operated by the latter; supplemental needle-bar actuating mechanism comprising a radially expansible cam carried by the cam shaft; cam expanding means carried by the cam shaft; and connecting means between one of said stop nuts and the expanding means.

12. In a straight knitting machine, yarn control mechanism comprising cooperating yarn guide carrier bars, a pair of opposed stops for certain of said carrier bars, and a reversely threaded spindle for moving said stops; needle-bar presser mechanism; a cam shaft for operating the latter; supplemental actuating means for the presser mechanism comprising a radially expansible cam carried by and rotative with the cam shaft; adjustable cam expanding means loosely carried by the cam shaft; and means turning said spindle and adjusting said expanding means in synchronism.

13. In a straight knitting machine yarn control mechanism comprising cooperating yarn guide carrier bars, a pair of opposed stops for certain of said carrier bars, and a reversely threaded spindle for moving said stops; needle-bar presser mechanism; a cam shaft operative upon the latter; supplemental actuating means for the presser mechanism comprising a radially expansible cam carried by and rotative with the cam shaft; adjustable cam expanding means loosely carried by the cam shaft; and a pattern chain

for turning said spindle and adjusting said expanding means in unison.

14. In a straight knitting machine yarn control mechanism comprising cooperating yarn guide carrier bars, a pair of opposed stops for certain of said carrier bars, and a reversely threaded spindle for moving said stops toward and from each other; needle-bar presser mechanism; a cam shaft operative upon the latter; supplemental actuating means for the presser mechanism comprising a radially expandible cam element carried by and rotative with the cam shaft; an adjustable segmental cam for expanding the latter; and spindle controlled means for adjustably moving said cams toward and from each other.

15. In a straight knitting machine yarn control mechanism comprising cooperating yarn guide carrier bars, a pair of opposed stops for certain of said carrier bars, and a reversely threaded spindle for moving said stops toward and from each other; needle-bar presser mechanism; a cam shaft operative upon the latter; supplemental actuating means for the presser mechanism comprising a radially expandible cam element carried by and rotative with the cam shaft; an adjustable segmental cam for expanding the latter; and spindle controlled means for adjustably moving said cams toward and from each other.

16. In a straight knitting machine yarn control mechanism comprising cooperating yarn guide carrier bars, a pair of opposed stops for certain of said carrier bars, and a reversely threaded spindle for moving said stops toward and from each other; needle-bar presser mechanism; a cam shaft operative upon the latter; supplemental actuating means for the presser mechanism comprising a radially expandible cam element carried by and rotative with the cam shaft; an adjustable segmental cam for expanding the latter, loosely carried by the cam shaft and concentrically shiftable thereon; and a pattern chain for cooperatively turning said spindle and moving the concentrically shiftable cam segments toward and from each other.

17. In a straight knitting machine the combination with adjustable yarn-control mechanism comprising cooperating yarn guide carrier bars, a pair of opposed stops for certain of said carrier bars, and a reversely threaded spindle for moving said stops toward and from each other; needle-bar presser mechanism; a cam shaft operative upon the latter; of supplemental actuating means for the presser mechanism comprising a radially expandible cam member fixed on said cam shaft; means for expanding said cam mem-

ber controlled by the spindle; and pattern mechanism for turning the spindle step-by-step in either direction.

In testimony whereof I affix my signature.

GOTTLOB BITZER.
